Num & Co
ATTORNEY

UNITED STATES PATENT OFFICE.

FREDERICK BENSON, OF SAN FRANCISCO, CALIFORNIA.

EGG BEATER.

Application filed July 5, 1923. Serial No. 649,571.

To all whom it may concern:

Be it known that I, FREDERICK BENSON, a citizen of the United States, and a resident of San Francisco, county of San Francisco, and State of California, have invented 5 a new and useful Egg Beater, of which the following is a specification.

This invention relates to egg beaters and has for its primary object the provision of 10 a device of this character which is simple of construction, positive and quick of action, and which will consist of coacting parts wherein continuous rotary action of a hand-controlled element will be converted 15 into oscillatory motion and applied as a motive means to drive the agitator of the device.

A further object of the invention is to 20 provide a device of this character which, aside from its reliability of action, will consist of parts that are designed and relatively 25 associated, whereby same will not be prematurely disorganized and wherein such parts will not be strained seriously during ordinary use of the device.

In the drawings:

Figure 1 is a vertical section through the device with parts in full lines;

Figure 2 is a front elevation of the device.

In carrying the invention into practice I use a frame (5) having a yoke (6) at its lower end which terminates in a combined foot and bearing (7). Said frame is provided with a vertical arm (8) which terminates at its upper end in a hand hold (9). Intermediate of its ends the said arm (8) is offset at (10). Mounted upon a bearing pin (11) on the arm (8) at a point 40 above said offset portion (10) is a rotary wheel (12) having a crank handle (13) whose pin (14) is provided with an annular groove (15). The grooved portion of this pin is accommodated by the elongated 45 slot (16) in an oscillating arm (17). This arm is mounted to rock on a pin (18) carried by said offset portion (10) of the bracket. The lower end of this oscillating arm is provided with an arcuate rack (19) or the 50 equivalent thereof. This rack is super-

posed with respect to a lateral bearing extension (20) which is located at the joinder of the arm (8) with the yoke (6). Passing through said bearing extension (20) is a shaft (21) whose upper end is provided 55 with a gear wheel (22) in mesh with the teeth (23) of said rack (19).

Said shaft (21) is permanently fixed at (22) to the cross bar (24) of an agitator (25). The cross bar (26) of said agitator 60 is connected by a bearing pin (27) with the aforesaid foot (7) of the yoke (6). This agitator consists of arcuate blades (28-28) which are preferably diametrically positioned, and as illustrated these blades are 65 provided with effective agitating ribs or flanges (29) which are perforated as at (30).

From the construction described herein it is seen that continuous rotation of the crank wheel (12) will impart continuous oscillations to the arm (17) and that incident to the coacting relation of the rack (19) to the agitator the latter will be continuously oscillated. In other words, rotary motion of the said crank wheel (12) will be instantly converted into oscillatory motion at the agitator. I find that an agitator which is oscillated as aforementioned is exceedingly positive and effective of action, and that by gearing the agitator to the oscillating arm (17) in the manner herein stated, the device can be subjected to unusually rough usage without causing the coacting parts of the device to be freely dislocated. While I have described that the oscillating arm (17) is provided with an integral arcuate rack which I employ as a power transferring means between the crank wheel (12) and the agitator (25), I will have it clearly understood that changes within 80 the scope of the appended claim may be made without departing from the spirit of my invention. In other words, in lieu of an integral rack, the lower portion of the arm (17) may have its ends connected by 85 a chain and the latter may be in constant mesh with a sprocket wheel on the upper end of the agitator shaft (21).

I claim:

An egg beater comprising a frame formed 100

of a single piece of metal bent to provide a yoke having a horizontal foot at its lower end, a lateral bearing extension disposed in parallel spaced relation to the foot, and an arm having an offset portion; an agitator shaft journaled in the foot and in said extension, a rocker mounted to oscillate on said offset portion and provided with a gear

surface, a gear on the agitator shaft in mesh with said gear surface, an agitator on said shaft, and a crank wheel mounted to rotate on said frame and having a driving connection associated with said rocker to actuate same. 10

FREDERICK BENSON.
